UNITED STATES PATENT OFFICE.

JOHN S. MONAGHAN, OF ROCHESTER, NEW YORK, ASSIGNOR TO GERMAN-AMERICAN
BUTTON COMPANY, OF ROCHESTER, NEW YORK, A CORPORATION OF NEW YORK.

DESIGN FOR A BUTTON.

50,845.

Specification for Design.

Patented May 29, 1917.

Application filed April 4, 1917. Serial No. 159,787. Term of patent 3½ years.

To all whom it may concern:

Be it known that I, JOHN S. MONAGHAN, a citizen of the United States, and a resident of Rochester, Monroe county, State of New York, have invented a new, original, and ornamental Design for Buttons, of which the following is a specification.

My design is represented in the accompanying drawing, in which:

Figure 1 is a plan view of a button showing my new design.

Fig. 2 is a side elevation looking in the direction of the arrow 2 in Fig. 1.

Fig. 3 is a section on line 3—3 of Fig. 1.

The button is circular and is provided with a raised base the upper exposed surface of which is curved. Projecting from the

center of the base is a dome shaped portion having four flattened faces of equal size and shape, 90° apart. The base of each flattened face has a horizontal step projecting outwardly therefrom.

I claim—

The ornamental design for a button substantially as shown and described.

In witness whereof I have hereunto set my hand at the borough of Manhattan, city and State of New York this seventeenth day of March 1917.

JOHN S. MONAGHAN.

In presence of—

ISABEL R. RICHARDS,
ZITA M. GRAHAM.
